LIGHTER

Kenneth M. Van Norman, East Moline, Ill.

Application February 18, 1953, Serial No. 23,671

Term of patent 14 years

(Cl. D48—27)

To all whom it may concern:

Be it known that I, Kenneth M. Van Norman, a citizen of the United States, residing at East Moline, in the county of Rock Island and State of Illinois, have invented a new, original, and ornamental Design for a Lighter, of which the following is a specification, reference being had to the accompanying drawings, forming a part hereof.

Figure 1 is a top plan view of a lighter, showing my new design;

Figure 2 is a side elevational view thereof; and

Figure 3 is a cross sectional view taken on the line 3—3 of Figure 1.

I claim:

The ornamental design for a lighter, as shown.
KENNETH M. VAN NORMAN.
